CLAIM

The ornamental design for a bible, as shown and described.

DESCRIPTION

FIG. 1 is a front plan view showing my design; FIG. 2 is a rear plan view thereof; FIG. 3 is a top elevation view thereof; FIG. 4 is a bottom elevation view thereof; FIG. 5 is a first side elevation view thereof; FIG. 6 is a second side elevation view thereof; FIG. 7 is a perspective view thereof; and, FIG. 8 is a plan view showing the bible open and the scale is reduced to allow the bible to fit on the page. The broken lines depict environment and form no part of the claimed design.

1 Claim, 8 Drawing Sheets(56)
